UNITED STATES PATENT OFFICE.

JOHN FISH FARRINGTON, OF FLUSHING, NEW YORK, ASSIGNOR TO WESTERN ELECTRIC COMPANY, INCORPORATED, OF NEW YORK, N. Y., A CORPORATION OF NEW YORK.

WAVE TRANSMISSION SYSTEM.

Application filed September 28, 1921, Serial No. 503,906. Renewed June 3, 1927.

This invention relates to improvements in two-way radio telephone systems and other similar signaling systems.

A type of system hitherto invented by the present applicant is one in which a certain portion of the energy of the outgoing carrier frequency wave is combined with the received signals to produce an auxiliary carrier wave. When signals are being transmitted, the auxiliary carrier wave is modulated in accordance with the transmitted signals; when signals are being received, the auxiliary carrier wave is modulated in accordance with the received signals; and when transmission and reception of signals occur simultaneously, the auxiliary carrier wave is modulated in accordance with both the received and transmitted signals. A particular instance of the application of such a system is in a radio telephone system for a two-way conversation wherein transmission and reception ordinarily take place alternately and not simultaneously. In case however, one party desires to interrupt or break in upon the conversation of the other, this is accomplished without the manipulation of any switch or the performance of any act other than merely talking into his telephone transmitter as is the case on an ordinary telephone line.

Objects of the invention are to improve the selectivity of the above mentioned and other types of system, to provide for the connection of such systems to ordinary telephone lines whereby conversations can take place partly by radio and partly over line wires, to provide arrangements whereby the amount of energy from the local transmitter impressed on the receiving circuit will not be sufficient to impair the efficiency of the receiving circuit, to provide for any desired degree of discrimination against the energy from the local transmitter in favor of energy from the distant transmitter, to provide channels for the transmission and reception of telegraph or calling signals on the same carrier wave or waves on which telephone transmission is accomplished, and to provide other novel improved features as herein-after described and claimed.

Means for attaining one or more of the above objects may be embodied in various systems. In the preferred form, as described herein, the transmitting antenna is

connected to any suitable kind of radio telephone transmitter and the receiving antenna is connected to a suitable selective circuit to select the received waves and combine them with energy of the transmitted wave frequency. The receiving antenna is preferably designed to discriminate to a desired extent against waves of the transmitted frequency. The combined waves produce a combination frequency which is selectively transmitted and amplified and combined with waves of a third frequency to produce a second combination frequency which is selectively transmitted and amplified and thereafter detected to produce the desired signal. The output circuit of the detector which performs the final detection is connected to a telephone line, to which is also connected, in conjugate relation, the input circuit of the radio telephone transmitter. A calling or telegraphing channel is superimposed upon the talking channel in a manner herein-after described.

For a more detailed description of the invention, reference is made to the accompanying drawings, wherein Fig. 1 is a circuit diagram of a complete system embodying the invention, and Figs. 2 and 3 illustrate modified forms of antenna circuit which may be used.

The circuit T constitutes a radio transmitter of any suitable type. As herein illustrated, high frequency oscillations from a source 1 of 800,000 cycles per second are impressed upon a thermionic amplifier tube 2 to the output circuit of which is connected an input circuit of a higher power thermionic amplifier 3. The output circuit of the amplifier 3 is connected to the antenna 4 which typifies any suitable radiating circuit. A variable impedance system V is controlled by speech or other signaling waves transmitted over the telephone line TL. A circuit 5 connects the telephone line with the input circuit of the system V. A space current source 6 supplies the amplifiers 2 and 3 and the system V through the iron core choke coil 7 which is designed to have a high inductive reactance for variations of speech frequencies. Radio frequency choke coils 8 serve to offer a high impedance to radio frequency currents, but a relatively low impedance to speech frequency currents. When the generator 1 is operating and sig-

naling waves are being received from the circuit 5, there will be produced in the antenna 4 and radiated therefrom, signal modulated radio frequency waves. Thus, if the frequency of the generator 1 in cycles per second be designated f_1 , there will be radiated in addition to the frequency f_1 , side frequencies $f_1 \pm s_1$, where s_1 designates the signaling frequency. This is indicated by the legend $f_1 \pm s_1$, placed adjacent the antenna 4. Similar legends will be used throughout this specification to designate modulated carrier waves.

The receiving antenna 9 is preferably tuned by means of a tuning capacity C or other suitable devices to the mean frequency of the high frequency signaling waves which are to be received. A tuned loop resonant circuit 10 tuned approximately or exactly to the frequency f_2 may be placed in the antenna 9 for causing the antenna circuit to discriminate against oscillations of the frequency f_2 . The circuit 10 may be adjusted by changing its tuning or resistance to give any desired degree of discrimination equal to or less than the maximum which might be secured by proper adjustment. Coupled to the antenna 9 is a circuit 11 which is likewise preferably tuned to the mean of the received frequencies.

It will first be assumed that a carrier wave modulated by a single signaling wave and represented by $f_1, f_1 \pm s_1$, is to be received from a certain station with which communication is to be had. The communicating station may be assumed to be transmitting on a carrier wave of 1,030,000 cycles, that is, $f_1 = 1,030,000$. This 1,030,000 cycle wave with its side frequencies will be superimposed upon the 800,000 cycle wave from the antenna 4 in the input circuit of detector D_1 . There will result in the output circuit of the detector D_1 a current component having a carrier frequency of 230,000 cycles with side frequencies. These frequencies will be amplified by the amplifier A, transmitted through the band filter BF, and impressed upon the input circuit of the detector D_2 . The amplifier A typifies any suitable thermionic or other amplifier having one or more stages. A generator 12 is also coupled to the input circuit of the detector D_2 , and supplies thereto a current having a frequency of 200,000 cycles. Let it be supposed that the switch 13 is closed. In the output circuit of the detector D_2 will be produced a current having a carrier frequency component of 30,000 cycles with side bands resulting from modulation. These currents will be selected by the band filter or tuned circuits BF_2 , amplified by the amplifier A_2 , and impressed upon the input circuit of the detector D_3 . The positions of band filter BF_2 and amplifier A_2 may be interchanged. To the output circuit of detector D_3 is connected a

speech frequency band filter SF adapted to pass a range of frequencies of from 200 to 2,000 cycles as indicated on the drawing. The filter SF therefore transmits freely those frequencies which are most essential for the reproduction of speech to the input circuit of the low frequency amplifier LFA which may be of the thermionic or any other suitable type. The output circuit of the amplifier LFA is connected to one of the windings of a three coil transformer 14, ordinarily known as a hybrid coil. The transformer 14 has one pair of terminals connected to the telephone transmission line TL and another pair of terminals connected to a balancing net BN comprising electrical impedance elements adapted to simulate the impedance of the line TL at speech frequencies. As will be noted the circuit 5 is connected to the coil 14 conjugately with respect to the output circuit of the amplifier LFA so that if the balance is perfect current variations in the output circuit of the amplifier LFA will produce no potential difference across the terminals of the circuit 5. However, a large degree of unbalance will not interfere with efficient operation, as explained hereinafter.

A telegraphing or signaling channel is superimposed upon the speech frequency channel. By means of this, the various carrier waves may be modulated in accordance with some frequency either above or below the speech range so as not to interfere with speech. In the present instance, a frequency of 150 cycles is used. A 150 cycle generator 15 is included in circuit with a key 16. When the key 16 is closed, the generator 15 will transmit an alternating current of 150 cycles through the speech frequency choke coils 17 to the input circuit of the variable impedance system V. Outgoing waves from the transmitter T will thereupon be modulated in accordance with the 150 cycle wave. A filter SF is included in the circuit 5 to prevent the passage of speech frequency components below 200 cycles. This filter may pass a range of from 200 to 2,000 cycles or all frequencies above 200 cycles. This prevents low frequency speech components from acting on the relay 18.

Let it be assumed that a distant communicating station is sending out a wave of 1,030,000 cycles modulated in accordance with a low frequency wave of 150 cycles. Then in the output circuit of the detector D_3 there will be a component of this low frequency. Since this component cannot be transmitted through the speech frequency band filter SF, it will traverse the low pass filter LPF which is designed to pass a range of frequencies of from 0 to 200 cycles. The receiving relay 18 will thereupon be actuated. The receiving relay 18 may constitute a telegraph sounder or other receiving in-

strument, or it may serve to close a circuit through a bell 19 or other equivalent calling or indicating device. This receiving relay is intended to typify any instrumentality or 5 device known in the art by which the 150 cycle current can be received. As so far described, it has been assumed that waves having a carrier frequency of 1,030,000 cycles are to be received. In this case it 10 would be proper to design or adjust the band filter BF to pass a range of frequencies of from 228,000 to 232,000 cycles. Greater selectivity would thus be obtained. However, for the purpose about to be described, 15 the band filter BF is in the present instance designed or adjusted to pass a range of frequencies of from 208,000 to 232,000 cycles. Let it be supposed that in addition to modulated waves of the carrier frequency f_1 , it is 20 desired to receive modulated waves of other carrier frequency f_{11} and f_{21} . Let f_{11} be 1,020,000 cycles and f_{21} be 1,010,000 cycles. Then in the output circuit of the detector D₁ will be produced modulated waves having carrier frequencies of 210,000 and 220,000 cycles in addition to those previously mentioned having a frequency of 230,000 cycles. When these various waves are combined with the waves from source 12, there 25 will result in the output circuit of the detector D₂, modulated waves of 10,000, 20,000 and 30,000 cycles, each modulated in accordance with its respective signal. Let it be assumed that the switch 13 is now opened, 30 which must be the case in order to receive the several waves described. This places in circuit the channels C₁ and C₂ in addition to the channel C₃. Then the band filter BF₁ in channel C₁ will select the 10,000 cycle modulated wave, band filter BF₂ in channel C₂ will select the 20,000 cycle modulated wave, and band filter BF₃ in channel C₃ will select the 30,000 cycle modulated wave. The 30,000 cycle modulated wave will as before 35 be detected to reproduce the signal or signals carried thereby in the manner hereinbefore described. This signal may be heard by a monitoring receiving telephone 20 connected across the output circuit of the band 40 filter SF, if desired. Likewise, an operator's transmitter 20' may be connected across the circuit 5, as illustrated. Components selected by the band filters BF₁ and BF₂ respectively may be detected and heard in receiving telephones 20 or impressed upon signaling lines such as the line TL if desired. It 45 will be understood, however, that whenever the transmitter T is operating, the waves selected by the band filters BF₁ and BF₂ will be modulated in accordance with any signal which is at that instant impressed upon the input circuit of the transmitter T. Thus, if the generator 15 is operating, there 50 will be produced in the output circuit of the detector D, a component having a frequency of 150 cycles. To suppress this current, band filter BFC₁ is included in the output circuit of the detector D. In case speech frequency waves are being impressed upon the input circuit of the transmitter T, these 70 will likewise be received in the channels C₁ and C₂ including the band filters BF₁ and BF₂. With the means described it is impossible to separate this speech signal from the incoming speech signals s_{11} and s_{21} , hence 75 it will be understood that in accordance with one method of operation it is not intended to use the channels C₁ and C₂ for receiving purposes at the same time that the transmitter T is operating to transmit speech signals. When, however, the transmitter T is active, but is transmitting only unmodulated waves or waves modulated in accordance with telegraphic currents outside of the speech range, then all three of the receiving 80 channels may be used, each to receive and detect an individual telephone or other signal transmitted from the same or different stations. The telegraph side tone from the local transmitter will be small or negligible in its effect on the telephone channels. As noted, when the channels C₁ and C₂ are to be used, the switch 13 is opened; when channels C₁ and C₂ are not in use, switch 13 85 may be either opened or closed but preferably closed. It should also be understood that the several receiving instruments of channels C₁, C₂ and C₃ or any two of them, as the receivers 20 and 21, may be brought to the ear of a single listener or otherwise connected to apparatus or a line so that a single listener can hear the messages incoming on all channels so connected. Each station from which the messages are received 90 can receive messages sent out from the station illustrated or from the other stations by providing a suitable number of selective receiving channels. In this manner several radio stations can communicate after the fashion of a several party conversation on 95 a party telephone line. 100

Various adaptations to meet special circumstances can be made in the system as illustrated. Thus, additional stages of amplification may be added wherever necessary, 105 or some of the amplifiers illustrated may be omitted. Additional selective circuits, or selective circuits other than band filters may be utilized. The generator 12 may be omitted. In this case, the modulated waves of 210,000, 220,000 and 230,000 cycles passed by the band filter BF would each be selected by a suitable selective circuit which would 110 discriminate against the other frequencies. After selection, each carrier wave would be 115 detected by a detector similar to the detector D₃ to reproduce the signal carried thereby. However, by making use of the generator 12 in the manner illustrated, additional selectivity is obtained. The invention is not 120 125 130

limited to the frequencies herein specified. Other frequencies may be selected as will be obvious to those skilled in the art. Furthermore, it is not essential that all of the band filters illustrated pass the exact range of frequencies indicated. Thus, for example, the filters BF_1 , BF_2 and BF_3 might be modified in a manner well understood to exclude either the upper or lower side band of the particular modulated wave passing therethrough. If the combined frequencies, produced by conjointly detecting incoming and outgoing waves, do not coincide with the range passed by the filter or selective circuit intended to pass them, the desired coincidence may be obtained by readjusting either of the frequencies, or by readjusting the selective circuit or substituting another in its place.

20 As to systems of this type, it has been suggested that they would be defective in that with large amplification in the receiving circuit and an unbalance of network BN with respect to the line TL the system would sing or oscillate by the cyclic transfer of energy from the output circuit of amplifier LFA through the transmitter T, antennæ 4 and 9, and receiving system R back to the point of beginning. By including the ether 25 between the antennæ as a conductive medium this forms a closed circuit. Experimental tests indicate that this kind of singing does not readily occur with large amplification and with considerable unbalance of the network BN. In a particular instance it has been found possible to substitute an open circuit for the network BN, leaving the hybrid coil connections otherwise unchanged, without producing singing. The circumstances 30 under which this occurred involved the use of a rather short telephone line TL and relatively small gains in the radio reception and detection circuit. It is within the purview of the invention to use the hybrid coil 14 or not and when it is used to attain any desired degree of balance which is necessary or convenient. Apparently the non-singing condition results from the fact that the losses around the closed circuit are at least equal to the gains. These losses result 35 in part from the fact that certain wave components are selected in the filters while others have their energy dissipated.

A feature of importance is the relative location of the amplifier A and the band filter BF. Instead of first selecting the intermediate frequency or frequencies and then amplifying their energy it has been found that increased selectivity results from placing the amplifier A in front of the band filter. The intermediate frequency and any accompanying disturbing waves are thereby first amplified and then the intermediate frequency is selected. When the band filter 40 BF is placed after the amplifier A, it has a

certain apparent disadvantage of causing to be impressed upon the amplifier A, undesired as well as desired frequencies. This apparent disadvantage is more than compensated for by the fact that the filter produces selective discrimination against amplifier noises created in the amplifier A which otherwise would be impressed upon the detector D_2 . Owing to the unavoidable detecting action of the amplifier A which cannot, in practical cases, be entirely eliminated, the various waves which are impressed upon its input circuit will be combined to produce sum and difference frequencies. When the band filter follows the amplifier all of these sum and difference frequencies will be suppressed except those which lie within the transmission band range of the filter. This feature, among others described, is equally applicable in any system wherein beating oscillations are employed to produce an auxiliary carrier wave, whether the beating oscillations are derived from the local transmitter or some other source.

Fig. 2 illustrates a form of receiving antenna which may be employed. A receiving loop 9' is coupled to the detector D_1 by an inductive connection to the circuit 11 or other suitable means. The loop 9' preferably includes an anti-resonant or loop circuit 10' tuned to the transmitter frequency to aid in keeping the energy of this frequency which is impressed on the receiver down to a value suitable to combine with that received from the distant station. The circuit including the loop 9' is tuned to the received frequency and the loop 9' is preferably directed at the distant station.

Fig. 3 illustrates another modified form of receiving antenna. In this instance, the antenna 9 is provided with a shunt path 22 to ground. This path 22 includes a loop circuit 23, tuned to the transmitted frequency f_2 . An additional circuit 24 serves to compensate for the reactance of the circuit 23 at the frequency f_1 and to tune the antenna as a whole to the received frequency. The circuit 11 is coupled to the circuit 24 in any desired manner. Any of the illustrated antenna systems or other modified forms may be used. For general purpose work that of Fig. 2 is to be preferred.

Having described the invention in detail and certain forms of apparatus desirable for use in carrying it into effect, the features inherent therein which are believed to be novel will be described in the appended claims.

I claim:

1. A signal transmission system comprising a station having means for transmitting high frequency waves, means for receiving high frequency waves, means for combining the energy of said waves to produce an auxiliary frequency wave, means for deriv-

ing signaling frequency waves from said auxiliary waves, a line terminating at said station, means at said station for transmitting said derived waves over said line to a distant point, and means for causing the transmitted high frequency waves to be modulated in accordance with waves received at said station over said line from a distant point.

10 2. A signaling system comprising means for transmitting signals by varying a carrier wave, means for receiving signals by combining received high frequency waves with waves of said varied carrier wave frequency, a telephone line, and conjugate connections from said line to the transmitting and receiving means respectively.

15 3. A two-way signaling system comprising means at one station, including an antenna, for producing and radiating a carrier wave, means including another antenna for receiving waves, said last mentioned means comprising means for combining waves received from said first mentioned antenna with 20 waves from a distant antenna, and two frequency translating devices in tandem for translating the frequency of the combined waves.

25 4. A station comprising an antenna for receiving energy from a distant station, a transmitting antenna, a detector for combining energy received by said receiving antenna with energy transmitted by said station from said transmitting antenna, and a 30 second detector for detecting the combined energy.

35 5. Terminal apparatus for two-way telephone communication comprising a radio transmitter including a transmitting antenna for transmitting on a given frequency, a radio receiver including an antenna tuned to a frequency differing from that of the transmitting wave, modulating apparatus for varying in accordance with speech the transmitted waves, the receiving antenna being discriminatory against the transmitted waves in favor of the received waves, said receiver including means for combining the transmitted and received wave energy to 40 produce other waves, and means to derive 45 telephone messages from the other waves.

50 6. A two-way signaling system comprising a receiver having means for receiving signals from a distant station, means for transmitting voice modulated waves, means for first combining said received waves with said transmitted waves to produce an auxiliary frequency wave, means for subsequently detecting said auxiliary wave to produce the received signal, additional means for modulating the transmitted waves in accordance with code signaling impulses, and means for receiving such impulses.

60 7. A two-way signaling system comprising

means for transmitting a signal modulated 65 wave, means for receiving by first combining received waves with energy of the transmitted wave frequency to produce an auxiliary carrier wave, means for subsequently detecting the auxiliary carrier wave to produce 70 the desired signal in combination with means for modulating the transmitted wave in accordance with speech, and means for causing non-interfering signaling changes in 75 said wave.

8. A two-way signaling system comprising in combination, means for transmitting a signal modulated wave, means for utilizing energy of the transmitted carrier wave frequency by combining it with the energy 80 of received waves to produce auxiliary carrier waves, means for detecting the auxiliary carrier waves to produce signals, and means for separating and separately receiving telephonic and telegraphic messages incoming 85 on the same carrier frequency of the received waves.

9. A two-way signaling system comprising means for utilizing the energy of the transmitted wave by combining it with energy 90 of received waves to produce auxiliary carrier waves, means for detecting the auxiliary carrier waves to reproduce signals, a band filter for selecting said auxiliary carrier wave, means for producing from the 95 selected wave a second auxiliary carrier wave, means for selecting said second carrier wave and means for deriving a signal therefrom.

10. In a two-way radio communication 100 system, a pair of distantly located stations one of which comprises a transmitter and a receiver, a transmitting antenna for said transmitter, a receiving antenna for said receiver, said transmitter including a source 105 of radio frequency continuous oscillations, the difference between the operating frequency of said source and the frequency of waves incoming from the distant station being a beat frequency above the usual frequencies essential in speech waves, means at 110 said receiver for detecting and indicating the signal components of said beat frequency, and a tuned loop trap circuit in said receiving antenna for offering a high impedance 115 to waves of the frequency produced by said source.

11. A two-way signaling system comprising means for utilizing energy of the transmitted wave frequency including means for combining it with energy of the frequency of received waves to produce auxiliary carrier waves, a plurality of signaling channels connected to the output circuit of said combining means, and means for translating the frequency of received waves a plurality of 120 times before detecting them to reproduce the signal.

12. Terminal apparatus for two-way radio telephone communication comprising a radio transmitter including a transmitting antenna for radiating waves to carry messages to a distant station, modulating apparatus for varying in accordance with speech the transmitted waves, a radio receiver comprising an antenna and means for combining energy of the frequency transmitted from said transmitter with energy of the frequency of waves received from a distant station to produce other waves, and means for deriving telephone messages from the other waves.
13. Terminal apparatus for a two-way radio communication system comprising a loop antenna for receiving energy from a distant station, a transmitting antenna for radiating energy to a distant station and to said loop antenna, a detector for combining waves received by said loop antenna from said transmitting station and from said distant station to produce beat frequency waves, and a second detector for detecting the beat frequency waves to reproduce signals.
14. The method of signaling which comprises combining at a carrier wave station incoming and outgoing carrier waves each modulated in accordance with signals to produce a wave different in frequency from each of said waves, detecting the wave resulting from the combination, and receiving the incoming signal separated from the outgoing signal.
15. In a radio receiving system, a detector and a selective circuit operatively associated therewith having fixed selective elements, a receiving circuit, a translating device between said receiving circuit and said selective circuit, an auxiliary station and a source of oscillations thereat, said auxiliary station being sufficiently distant from said selective circuit so that the selective devices cannot be adjusted from the auxiliary station, and means to supply oscillations from the auxiliary station to said translating device to translate received oscillations into oscillations which may be transmitted through the selective circuit.
16. A station comprising an antenna for receiving waves from a distant station, a transmitting antenna, a detector for combining waves received by said receiving antenna with waves transmitted by said station from said transmitting antenna, a second detector for detecting the combined waves, and an indicating device for indicating the waves produced by the last mentioned detection.

In witness whereof, I hereunto subscribe my name this 24th day of September A. D., 1921.

JOHN FISH FARRINGTON.
